VENTILATING APPARATUS FOR TOILET
HOPPERS

Herbert P. Wheeler, Springfield, Mo.

Application July 14, 1944, Serial No. 544,847

1 Claim. (Cl. 230—117)

This invention relates to apparatus for ventilating toilet hoppers, one of the objects being to provide a suction fan of new and novel construction which is substantially noiseless and free of vibration and can be set up at any point either close to or remote from the hopper and, when set in motion, will withdraw air from beneath the seat on the hopper so that the spread of objectionable odors thus can be prevented.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings:

Figure 1 is a top plan view of the complete apparatus, a portion of the hopper to which it is joined being also illustrated.

Figure 2 is a front elevation of the ventilating fan and its motor, a portion being broken away.

Figure 3 is an enlarged section on line 3—3, Fig. 2.

Figure 4 is an enlarged section on line 4—4, Fig. 1.

Referring to the figures by characters of reference, 1 designates a portion of the back of a toilet hopper on which is mounted a hollow, box-like intake member 2 having a flat inlet tube 3 extended therefrom at a point where it can project beneath the movable cover 4 of the hopper. One end of the member 2 has an outlet 5 for the reception of a flattened nipple 6 to which is connected a pipe 7 leading to the casing of a suction fan. This pipe can be rigid or flexible and can be extended any desired distance away from the hopper. In some cases the suction fan used as a part of the apparatus can be located in the basement of a building and the suction pipe leading thereto can be extended to a hopper located at a point on an upper floor of the building.

The means employed for effecting a suction of air from beneath the lid or cover of the hopper has been illustrated in detail in Figs. 2 and 3. It includes an electric motor 8 rigidly joined to a bottom plate 9 by means of bolts 10 extending through flanges 11 extending from the housing of the motor 8 and adjacent to its corners, the bottom or base plate 9, has posts adjustably connected thereto, these posts being mounted on

shock-absorbing cushions 13 of rubber or other suitable material.

Blocks of wood or the like indicated at 14, can be interposed between the posts and the cushions 13 and the upper ends of the posts can be screw-threaded so as to engage nuts 15 secured on the base or bottom 9. Thus by rotating the posts they can be adjusted longitudinally, thereby providing efficient means for insuring proper placement of the motor on a floor or other supporting surface.

The housing of the motor 8 is provided, at one end, with radial ears 16 to which a ring 17 is secured by means of bolts 18. This ring is welded or otherwise securely fastened to the back plate 19 of a housing and, as shown, this back plate has a concentric offset portion forming a circular recess 20 and also is provided with an annular out-turned flange 21.

The shaft 22 of the motor 8 is extended through the plate 19 and has keyed or otherwise secured thereto the hub portion 23 of a fan. The blades of this fan are curved away from the hub in the direction of rotation, as indicated at 24 in Fig. 3, and all of the blades extend to the periphery of a disk 25 secured to shaft 22 and positioned for rotation within the recess 20.

A substantially cylindrical housing 26 has an open side in which is fitted the annular flange 21 to which the housing is secured by means of bolts 30 or the like. This housing completely surrounds the fan formed by disk 25, blades 24 and hub 23 and is provided at the center of that side thereof remote from the motor, with an inlet tube 31 which, as shown, can be flared toward the housing, the flared portion being indicated at 32.

A tangential outlet tube 33 opens through the periphery of the housing 26 and is connected to that end of the pipe 1 remote from the hopper.

In practice the nipple 6 is wedged into the open end of the member 2 on the back of the hopper and is connected by the pipe 7 to the inlet tube 31 of the fan housing. The fan is adapted to be rotated at low speed whenever a circuit thereto is closed and, while it is not so shown, it is to be understood that a switch in the form of a button or the like can be located adjacent to the hopper so that the circuit can be closed at will so as to effect an exhaust of air from beneath the seat whenever desired. The operation of the motor results in rotation of the fan blades at high speed and the blades are so constructed that they will effect a strong suction

of air through the pipe 7 and tube 31 and expel the air through the outlet tube 33.

As the fan is mounted on cushioning means noise due to vibration will be reduced to the minimum and, because of the particular construction of the fan there will be little, if any, vibration to absorb. Vibrations are further reduced because the fan operates at low speed. The fan and its housing are assembled readily and the entire structure is so simple that it will not easily get out of order.

What is claimed is:

In a ventilating attachment for toilet hoppers, a slow speed motor having a housing and a shaft, adjustable cushioned supporting means for the

housing, a plate secured to one end of the housing and having a concentric recess in one side and an annular flange projecting beyond its other side, a disk rotatable within the recess and secured to and driven by the shaft of the motor, a hub secured to said shaft, curved blades extending from the hub to the margin of the disk and rotatable in one direction to effect a suction, a housing having an open side fitted on and surrounding the flanged portion of the plate, means for securing said housing to the flanged portion, and a marginal outlet and a central inlet in the housing, said blades, when rotating, constituting means for forcing air from the inlet to the outlet.

HERBERT P. WHEELER.
